UNITED STATES PATENT OFFICE.

CHARLES H. BOARDMAN AND JOHN W. MISKELL, OF VIVIAN, WEST VIRGINIA, ASSIGNORS OF ONE-THIRD TO THEOPHILUS KING, OF QUINCY, MASSACHUSETTS.

APPARATUS FOR SEPARATING BONE, SLATE, &c., FROM COAL.

SPECIFICATION forming part of Letters Patent No. 734,219, dated July 21, 1903.

Application filed September 30, 1902. Serial No. 126,344. (No model.)

To all whom it may concern:

Be it known that we, CHARLES H. BOARDMAN and JOHN W. MISKELL, of Vivian, in the county of McDowell and State of West Virginia, have invented certain new and useful Improvements in Apparatus for Separating Bone, Slate, &c., from Coal, of which the following is a specification.

This invention relates to certain new and useful improvements in the apparatus for separating bone, slate, and the like from coal.

The invention has for its object the production of a simple and inexpensive apparatus by means of which the coal may be conveyed from the mine in such manner that the bone, slate, and other impurities are automatically brought to view, whereby they may be readily removed and kept separate from the good coal without interruption to the delivery of the latter to the place of storage.

The invention will be hereinafter fully set forth, and particularly pointed out in the claims.

In the accompanying drawings, Figure 1 is a side elevation, partly in section, of the hopper and smoothing-conveyer. Fig. 2 is an end view thereof. Fig. 3 is a side elevation of the delivery end of the apparatus. Fig. 4 is a plan view of the parts shown in Fig. 3.

Referring to the drawings, 10 designates a pit or well located, preferably, near the mouth of the mine and at a point where the mine-cars can conveniently dump their contents into the hopper 11, which is supported by a framework F, of any suitable structure. Said hopper is formed with upper converging walls A, preferably of timber, and a lower rectangular chute B, preferably made of steel or other suitable metal. The latter is supported by angle-irons 12, secured to timbers 13 of the framework F.

Resting upon timbers 14 are a series of horizontal angle-bars 15, which serve to brace opposite vertical angle-bars C, which are supported by the side walls of the chute B. The vertical angle-bars serve as supports for the parallel runways 16 of a "smoothing-con-

veyer" 17, working below the lower edge of the chute B and corresponding in width with the latter. The conveyer 17 passes around 50 pulleys 18 19, the former being provided with a suitable tension device 20.

On the shaft 21 of pulley 19 is keyed a pulley 22, which is connected by a belt 23 with a second pulley 24, keyed on a shaft 25, 55 mounted at the bottom of framework F. The runways 26 of the elevating-conveyer are mounted on inclined timbers running from the bottom of framework F to the delivering end of the apparatus, where are located the platforms 27 for the pickers, said platforms being preferably located at the top of the tipple or other storage-receptacle. An ordinary beaded conveyer 28, provided with transverse spaced-apart bars D, is passed 60 around drums 29, keyed to shafts 25 and 30, respectively, a suitable tension device being provided, as shown. On the shaft 30 is keyed a gear-wheel 31, which meshes with a suitable pinion 32 on a shaft 33, said shaft being 70 in turn rotated by suitable gearing 34, operated by a pulley 35, receiving power from any suitable source. A chute 36, preferably having converging branches, as shown in Fig. 4, is supported at any suitable point, preferably above the conveyer, and designed to conduct the bone, slate, and other refuse to some convenient storage-receptacle. 75

In practice the smoothing and elevating conveyers are so geared that the latter will 80 move at a considerably higher rate of speed than the former. The coal as it is mined is dumped into the hopper 11 and is guided by chute B to the conveyer 17. The latter being geared to a comparatively slow speed is 85 intended to level off the coal as it is dumped and deliver the same in minimum quantities to the elevating-conveyer 28, which conducts it to the tipple. It will be observed that the picking-platforms are arranged intermediate 90 of the receiving and delivery ends of the conveyer 28. The runways 26 of the latter are preferably curved to a horizontal plane to pass above the plane of the platforms 27. By

this means two workmen stationed on the platforms at X can readily detect the bone, slate, and other impurities as the material is brought up on the conveyer and throw them 5 out into chute 36. It frequently happens, particularly in soft-coal districts, that a small quantity of bone will be embedded in a large lump of coal, and in such instances the workmen on the picking-apron can retard the 10 progress of said lump for a sufficient time to "pick" off the good coal, whereby the refuse can be thrown out with little or no waste.

The advantages of our invention are at once apparent. Under the old methods now 15 in vogue the coal is usually conveyed direct to the tipple, and when it is desired to load a train for transportation several workmen, usually five or six, are placed in the car being loaded, the coal being delivered from the 20 tipple in small quantities, usually from a half-ton to a ton at a time. These workmen then pick off the bone and slate and throw it out of the car, additional coal being fed as the work progresses. The highest average 25 ever attained under this method is approximately five hundred tons in one day. By means of our improved apparatus we can dispense with the labor of from three to four men and handle from fifteen hundred to two 30 thousand tons per day, and this with far less manual exertion. We are also aware that it is common to separate slate, bone, &c., from coal by dumping the product from the mine on an inclined trough or "telegraph," where 35 the impurities are manually picked over as the coal slides down by gravitation, and also that it is old to convey coal and ore by means of belts from the mine to a chute and manually picking out the impurities in transit, 40 and hence we do not make claim to such devices. On the contrary, our invention contemplates means for spreading out the coal in layers of predetermined quantities to prevent overlying of the pieces and means for 45 causing said pieces to retain their relative positions while passing a given point at a predetermined speed, whereby the impurities may be manually removed without risk of tumbling or rolling lumps bruising or otherwise injuring the hands of the pickers. By 50 means of our invention the coal is far more thoroughly cleaned of the refuse, owing to the fact that the conveyer-compartments contain but minimum quantities of coal, all of 55 which is readily brought to view on the picking portion of the conveyer. In this way the refuse is not likely to be covered by the good coal, so as to be hidden from view, and being fed slowly and in a spread-out condition am- 60 ple opportunity is given the operators to throw off the refuse without wasting good coal and without interruption to the delivery of the latter to the tipple and without liability of having their work interrupted or their hands injured

by tumbling or rolling lumps. A still further 65 advantage lies in the fact that coal for the market can be at once loaded into the cars from the tipple without being picked over, thereby avoiding the delays incident to the latter process. It will also be noted that by employing the refuse-chute the bone, &c., which is usually employed in the making of coke can be directed to a suitable point of storage 70 without further handling.

We claim as our invention—

75

1. An apparatus of the character described comprising a picking-conveyer; means for spreading the coal, bone, slate, &c., thereon in a layer of predetermined quantity to prevent overlying of the pieces, and means for 80 causing the pieces to retain their relative positions while passing a given point to enable a picker to remove the bone, slate, and other impurities without interference by changes in position of some of the pieces, as set forth. 85

2. An apparatus for separating coal, comprising an elevating apparatus including a picking portion, and an apparatus for feeding coal to said elevating apparatus in predetermined quantities, said feeding and elevating apparatuses being geared to operate 90 at predetermined relative speeds, as set forth.

3. An apparatus for separating coal, comprising a smoothing-conveyer, a hopper leading thereto, an elevating-conveyer coacting 95 with said smoothing-conveyer, and a picking-apron intermediate of the ends of said elevating-conveyer, as set forth.

4. An apparatus for separating coal, comprising a smoothing-conveyer, a hopper leading thereto, an elevating-conveyer coacting 100 with said smoothing-conveyer, a picking-apron intermediate of the ends of said elevating-conveyer, and a refuse-chute located above said latter conveyer and leading from 105 said picking-apron, as set forth.

5. An apparatus for separating coal, comprising a smoothing-conveyer, a hopper leading thereto, an elevating-conveyer coacting 110 with said smoothing-conveyer, and a picking-apron intermediate of the ends of said elevating-conveyer, the runways of said latter conveyer being curved to a horizontal plane over said apron, as set forth.

6. An apparatus for separating coal, comprising a framework, a hopper supported thereby, a chute leading from said hopper, a smoothing-conveyer supported by said chute, and an elevating-conveyer coacting with said 115 smoothing-conveyer and having a picking portion, as set forth.

7. An apparatus for separating coal comprising a hopper, a chute leading therefrom, runways supported by said chute, a smoothing-conveyer working in said runways, and 120 an elevating-conveyer coacting with said smoothing-conveyer and having a horizontal picking portion, as set forth.

125

8. An apparatus for separating coal, comprising a hopper, a chute leading therefrom, angle-irons secured to said chute, brace-bars therefor, runways carried by said angle-irons,
5 a smoothing-conveyer working in said runways, and an elevating-conveyer coacting with said smoothing-conveyer and having a picking portion, as set forth.

In testimony whereof we have affixed our signatures in presence of two witnesses.
